UNITED STATES PATENT OFFICE.

EDWARD J. BRAUER, OF UNIVERSITY CITY, MISSOURI, ASSIGNOR TO BRAUER BROS.
MFG. CO., OF ST. LOUIS, MISSOURI, A CORPORATION OF MISSOURI.

GOLF BAG.

Application filed February 18, 1924. Serial No. 693,520.

This invention relates to golf bags adapted for the handling and carrying of golf clubs, etc.

A golf bag is rather a long structure and accordingly is unwieldy to carry. Accordingly it is usually dragged along the ground by a handle fastened thereto, especially where no caddy accompanies the player. In order to reduce the weight, the material of which the bag is composed of is ordinarily light, being usually composed of canvas or light leather, and stays are, therefore, provided in order to hold the bag in shape. A handle is arranged at the upper end of the bag by which this bag can be carried, but due to the fact that the device is unwieldy, the attachment of a handle to the body subjects the connection to such strains as to not only distort the bag, but also tear the connections of the handle to the bag body.

One of the objects of this invention, therefore, is to provide a golf bag which is not only suitably stayed to keep its shape, but is also so constructed that it can be transported without permanent distortion.

Another object is to connect a handle to the body and the stays in such a manner that the stresses are transmitted over a large part of the bag body and directly to the stays.

Another object is to provide a golf bag which is simple in construction, neat in appearance and economical to manufacture.

Further objects will appear from the detail description taken in connection with the accompanying drawing, in which:

Figure 1 is an elevation of a golf bag embodying this invention, the carrying strap being cut away to show the handle and its connections; and

Figure 2 is a section on line 2—2, Figure 1.

Referring to the accompanying drawing, 1 designates the body of a golf bag, which body may be of any suitable material, such as canvas, although it may be of leather. The bottom and top may be formed in any suitable and usual manner, the usual bottom band 2 and the usual top band 3 being provided, while a ring 4 surrounds the open end. Metallic stays 5 in leather pockets 6 stitched to the body connect the top and bottom bands, these stays being riveted to the

band 3 as shown at 7 and 8 respectively. Stitched to the body and dropping from the top band 3 is a reinforcement 9 which may be of leather and to which is attached the handle 10, as well as the carrying strap 11. A strap 12 passing underneath the reinforcement and attached thereto may also surround the body. A hanger loop 13 may also be attached to the band 3 by rivets 14. A pocket 15 of usual construction may also be provided. In fact, the parts so far described may be of any usual and suitable construction, and further description thereof is therefore unnecessary.

The bottom of the handle 10 passes through a slit in the reinforcement 9 and against the canvas and is secured by rivets 16 passing through the reinforcement, the handle and the body. The top of the handle also passes through a similar slit and is secured by rivets 17 also passing through the handle, the reinforcement and the body. Arranged, however, at the handle connection is a transverse brace 18 which passes underneath the reinforcement 9 and between it and the end of the handle and is secured by the rivets 17. The ends of the brace are, however, attached to the stays 5 by rivets 19 passing through the brace, the pocket 6, the stay 5 and the body. This brace is preferably of strong sheet metal so as to have considerable rigidity and so as to keep its shape. Staples or rivets 20 also additionally secure the reinforcement and body together above and below the brace. Lines of stitches 21 may additionally secure these parts together.

It will, therefore, be seen that the handle 10 and its reinforcement 9 are not only attached to the body of the bag, but they are also attached to the stays through the medium of the brace. A firm structure is, therefore, provided which, while it does not add materially to the weight of the bag, provides a means for distributing the connection between the handle and the body over a large part of the body. Accordingly the bag can be handled and even dragged, and given considerable wear without undue distortion to the body.

It is obvious that various changes may be made in details of construction without departing from the spirit of this invention;

it is, therefore, to be understood that this invention is not to be limited to the specific details shown and described.

Having thus described the invention, what is claimed is:

1. A golf bag comprising, an elongated body provided with a top band and having stays therealong, a handle attached to said body below said top band and intermediate 10 a pair of stays, and a transverse brace connected medially with said handle and at its ends to said stays.
2. A golf bag comprising, an elongated tubular body having stays therealong, a reinforcement extending therealong, a handle attached to said reinforcement, and a transverse brace connected medially with said reinforcement and at its ends to said body stays.
3. A golf bag comprising, an elongated body having stays therealong, a reinforcement extending therealong between a pair of stays, a handle attached to said reinforcement, and a transverse brace connected medially with said reinforcement and at its ends to said body stays.
4. In a golf bag having an elongated tubular body and a pair of stays extending along said body, the combination with a rigid brace extending transversely of said body and attached at each end to one of said stays, and a handle attached at its lower end

to said body and at its upper end to said transverse brace.

5. A golf bag comprising an elongated tubular body provided with a top band, a handle attached to said body below said top band, and a rigid transverse brace connected medially with said handle, and at its ends to said body. 35 40

6. A golf bag comprising an elongated body provided with a top band and having stays therealong, a handle attached to said body below said top band and intermediate a pair of stays, and a rigid transverse brace 45 connected medially with said handle and at its ends to said stays.

7. A golf bag comprising an elongated tubular body having stays therealong, a reinforcement extending therealong, a handle attached to said reinforcement and a rigid transverse brace connected medially with said reinforcement and at its ends to said body stays. 50

8. A golf bag comprising an elongated body having stays therealong, a reinforcement extending therealong between a pair of stays, a handle attached to said reinforcement, and a rigid transverse brace connected medially with said reinforcement and at its 55 60 ends to said body stays.

In testimony whereof I affix my signature this 16th day of January, 1924.

E. J. BRAUER.
